UNITED STATES PATENT OFFICE.

HOWARD M. NICHOLSON, ARTHUR D. NICHOLSON, GEORGE B. NICHOLSON, AND WILLIAM T. LOWERY, OF PITTSBURGH, PENNSYLVANIA.

VACUUM DISPENSING APPARATUS.

1,327,112.

Specification of Letters Patent.

Patented Jan. 6, 1920.

Application filed February 23, 1918, Serial No. 218,858. Renewed June 16, 1919. Serial No. 304,740.

To all whom it may concern:

Be it known that we, HOWARD M. NICHOLSON, ARTHUR D. NICHOLSON, GEORGE B. NICHOLSON, and WILLIAM T. LOWERY, 5 citizens of the United States of America, residing at Pittsburgh, in the county of Allegheny and State of Pennsylvania, have invented certain new and useful Improvements in Vacuum Dispensing Apparatus, of 10 which the following is a specification.

This invention relates to dispensing apparatus and it has for its object to provide an improved apparatus for dispensing fuel or lubricating oils for the use of motorists.

15 The apparatus is particularly designed for the purpose of dispensing gasolene and other volatile and explosive oils. Because of the strict fire regulations in some cities it is undesirable to place the main containing tanks of oils of this nature under air pressure. To avoid the necessity of putting the main containing tanks under pressure and at the same time to avoid the employment of a pump and the annoyance arising 20 from the necessity of starting the same whenever gasolene is to be dispensed, we propose to utilize the ordinary city water supply in conjunction with a novel type of vacuum creating means which will automatically 25 act to create a vacuum in the dispensing chamber and cause the gasolene to flow thereinto.

Further objects and advantages of the invention will be set forth in the detailed description which now follows.

35 In the accompanying drawing;

Figure 1 is a view partly in section and partly in side elevation of a dispensing apparatus constructed in accordance with the 40 invention and

Fig. 2 is a detail sectional view of a two way valve employed in conjunction therewith.

Like numerals designate corresponding 45 parts in both of the figures of the drawing.

The apparatus comprises a hollow pedestal 5 adapted to be located at the curb line and a superposed dispensing chamber comprising a glass cylinder 6 graduated as at 7 50 to indicate the number of gallons, a lower head 8 and an upper head 9 these heads being drawn together by bolts 10. A light containing dome 11 which may contain an incandescent bulb indicated at 12 is mounted 55 upon the top of the head 9, this dome not

only serving to indicate the location of receptacle 6 from afar, but, in conjunction with the light 12 serving as a means for illuminating the interior of the receptacle 6, it being understood that the light will shine 60 downwardly through the top 9 which is open at 9^a. A discharge neck 13 is provided with a controlling valve 14 and carries a flexible hose 15 adapted to discharge the contents of the dispensing receptacle 6 into 65 the tank of an automobile. A main reservoir or container 16 is located below the side-walk 17 and is provided with a filling pipe 18. A discharge pipe 19 leads from the container 16 to the bottom of the receptacle 70 6 and a check valve 20 permits the passage of the gasolene or other fuel oil into the receptacle 6 but prevents return movement of such oil. A vacuum or suction pipe 21 leads from the upper part of the receptacle 6 to 75 the top of a tank 22. A water supply pipe 23 from a city water supply line leads to the tank 22. A float 24 controls a valve 25 of a usual and well known construction such as are employed in closet flushing tanks 80 wherein the valve is automatically shut off after the float 24 has reached a predetermined height. A discharge line 26 to a sewer (not shown) leads to the bottom of the tank 22 and a ball valve 27 closes the 85 entrance to this pipe. Guides 28 insure the proper movement of the valve 27. The stem 29 of the valve 27 passes through the lever 30 which connects the float 24 with the valve 25 and the stem 29 is provided with a collar 90 31 above the lever 30. When the float is raised by the inflowing water to such a position that it contacts with the collar 31 the ball 27 will be lifted from its seat. During the upward movement of the water the air 95 contained within the tank 22 will be driven out through an outwardly opening check valve 32. Consequently when the ball valve 27 is lifted from its seat the water will not immediately flow into the pipe 26 because of 100 the lack of air thereabove. It is to be understood that the ball valve 27 is of the type employed in closet flushing tanks. That is, it is of a type which is held seated after once becoming seated, by the pressure of the 105 water thereon, but when once released from its seat is held in an elevated position by its buoyancy until practically all of the water is discharged from the tank.

Disposed within the length of the vacuum 110

pipe 21 is a two way valve 33 (see Fig. 2). This valve comprises a plug 34 which, when turned to one position, establishes communication straight through the pipe 21 and when turned to another position establishes communication between the interior of the receptacle 6 and the atmosphere through a port 35.

If, with the tank filled with water to a position where the float 24 has lifted the valve 27 from its seat, the valve 33 be manipulated to establish communication between the receptacle 6 and the tank 22, air from the interior of the receptacle 6 (which it will be understood is a fluid tight receptacle) passes through the pipe 21 and immediately the water begins to flow through the pipe 26 to the sewer. The continued downward movement of this water creating a vacuum 20 in tank 22 and, through pipe 21, in the receptacle 6 causes the gasoline from the storage tank 16 to flow upwardly through pipe 19 until the desired amount as indicated by the graduations 7 has entered the receptacle 25. Thereupon the two way valve 33 is moved to establish communication between the atmosphere and the interior of the receptacle 6, whereupon the contents of this receptacle will be discharged through the extension 13 and pipe 15 if the valve 14 be open, it being apparent that the gasoline cannot flow back into the storage tank 16 because of the check valve 20.

After all of the water has been discharged 35 from the tank 22 the valve 27 will seat and then the tank 22 will again fill with water preparatory to repeating the operation whenever the operator sees fit to manipulate valve 33 to establish communication through 40 the vacuum pipe 21 between the interior of receptacle 6 and the said tank 22.

If desired a pipe 36 may be disposed in position to conduct the air discharged from tank 22 during the upward movement of 45 the water therein, to a remote point, as for example, above and outside of the building in which the tank is located, in order to avoid the possibility of discharging carbureted or explosive vapors within the building.

From the foregoing description it will be seen that the means herein shown and described will provide for the dispensing of gasoline with a minimum of annoyance and expense. The pressure of the city water supply is utilized to place in position a body of water ready to act in the creation of the necessary vacuum whenever the valve 33 is opened and it is to be noted that this preparatory step is taken prior to the opening of the valve. Consequently when the valve is open the response of the apparatus is instantaneous and gasoline may be served to waiting customers in a minimum time. In 60 short, during the time that the gasoline is

being discharged from the receptacle 6 into the waiting automobile the tank 22 will be filling to provide a considerable volume of water ready to rush into the sewer under gravity and to thereby quickly create the necessary vacuum to supply the gasoline for the next car, which may be waiting.

It is to be understood that the invention is not limited to the precise construction set forth but that it includes within its purview whatever changes fairly come within the spirit of the appended claims.

Having described our invention what we claim is:

1. In a system of the character described, the combination with a dispensing receptacle, of a storage receptacle, a connection therebetween, a check valve in said connection, a vacuum creating tank, a source of water supply under pressure leading thereto, an outlet therefrom, the movement of the water from the tank acting to create a vacuum therein, a connection between the vacuum tank and the dispensing receptacle, a controlling valve in the last named connection for establishing communication between the vacuum creating tank and the dispensing receptacle, means for admitting air to the interior of the dispensing receptacle and from said receptacle to the tank, and a discharge pipe leading from the dispensing receptacle.

2. A system of the character described comprising a storage receptacle, a dispensing receptacle, a connection therebetween, a check valve in said connection, a vacuum creating tank, a source of water supply leading thereto, a sewer connection leading therefrom, a float valve controlling said sewer connection, a float controlling the passage of water to the interior of the vacuum creating tank, means for causing the last named float to actuate the float valve after a predetermined upward movement of the float, an outwardly opening check valve for permitting the passage of air from the vacuum creating tank during the upward movement of the water therein, a connection between the vacuum creating tank and the dispensing receptacle and a two way valve in said pipe, said two way valve when moved to one position establishing communication between the vacuum creating tank and the dispensing receptacle and when moved to another position establishing communication between the dispensing receptacle and the atmosphere.

3. In combination a storage tank, a dispensing receptacle, a discharge pipe leading from the dispensing receptacle, a pipe establishing communication between the storage tank and the dispensing receptacle, a check valve in the last named pipe, a vacuum creating tank, a source of water supply leading thereto, a valve for controlling the passage of water from the source of water supply to

the interior of the tank, a float for controlling said valve, a lever connecting said float with said valve, a sewer connection leading from said vacuum creating tank, a ball valve for controlling the entrance to said sewer connection, a stem carried by said ball valve and an element carried by said stem with which the lever of the float engages to thereby elevate the ball valve upon upward move-

ment of the float and an outwardly opening 10 check valve carried by the vacuum creating tank.

In testimony whereof we affix our signatures.

HOWARD M. NICHOLSON.

ARTHUR D. NICHOLSON.
